(57) **CLAIM**

The ornamental design for a bottle stoppering machine, as shown and described.

DESCRIPTION

FIG. 1 is a rear view, showing our new design;
FIG. 2 is a side view thereof;
FIG. 3 is a front view thereof;
FIG. 4 is a bottom view;
FIG. 5 is a top view thereof;
FIG. 6 is a front perspective view thereof;
FIG. 7 is a rear perspective view thereof;
FIG. 8 is a front perspective view from a bottom angle thereof; and,
FIG. 9 is a rear perspective view from a bottom angle.
